UNITED STATES PATENT OFFICE.

JOHN J. MACK, OF SALEM, MASSACHUSETTS.

WALL TIE.

Application filed December 28, 1922. Serial No. 609,476.

To all whom it may concern:

Be it known that I, JOHN J. MACK, a citizen of the United States, residing at Salem, in the county of Essex and State of Massachusetts, have invented certain new and useful Improvements in Wall Ties, of which the following is a specification.

A serious objection to the brick wall type of building construction is the fact that a brick wall of the usual thickness will wet through in a hard driving rain of long duration. This fact has long been recognized and it has been customary, therefore, to construct such a wall with a vertical air space in it. That is, the wall is double, consisting of inner and outer wall sections separated by an air space. It is necessary to bond or tie these two sections of the wall together at intervals, and this has usually been done heretofore by placing bricks at intervals lengthwise across the air space, the opposite ends of such bricks being anchored in the two walls. These brick ties have the advantage of permanency and of being economical to use, but they have the disadvantage of conducting water from the outer to the inner wall, due both to capillarity and also due to the fact that they present broad surfaces across which the water can flow from one wall to the other. A further objection to the brick tie is that mortar which drops down between the inner and outer sections of the wall during the process of erecting it, lodges on the bricks and thus forms an additional porous body which conducts water from one wall to the other.

In order to obviate the necessity of using a brick tie, a great many forms of metal wall ties have been devised. All of them, however, of which I have been able to learn, are open to the objection that they corrode or rust out after relatively few years so that they become absolutely worthless. Most of these prior constructions, also, have the same objection as the brick tie so far as collecting mortar is concerned, and they are open to the further objection that water running down the inner face of the outer wall, will collect on them and run across them to the inside wall, where it will ultimately soak through the bricks in the latter wall. The result is that notwithstanding these prior attempts to devise a satisfactory metal wall tie, the brick tie is still

used more commonly than any other form of tie.

The present invention relates to wall ties and has for its chief object to devise a metal wall tie which will be permanent, economical to manufacture, convenient to use, will absolutely prevent water from travelling across it or through it from one wall to the other, and which generally will satisfy the practical requirements for a device of this kind.

The nature of the invention will be readily understood from the following description when read in connection with the accompanying drawings and the novel features will be particularly pointed out in the appended claims.

Figure 1 is a plan view of a wall tie embodying the present invention;

Fig. 2 is a side elevation of the device shown in Fig. 1;

Fig. 3 is an end view of the device shown in Figs. 1 and 2;

Fig. 4 is a cross sectional view on the line A—A, Fig. 1; and

Fig. 5 is a cross sectional view on the line B—B, Fig. 1.

The wall tie shown comprises two flat end portions 2 and 3, designed to be anchored, respectively, in the inner and outer sections of a wall of the character described above with the plate in a horizontal position. In order to facilitate the secure anchoring of the plate in the wall, the upper and lower surfaces of the end portions are corrugated, as clearly shown, and each is provided with a central perforation 4. Preferably, also, the end portions are wedge-shaped or tapered toward each other, as clearly illustrated, so that when they have once been embedded in the wall sections they will effectually resist any tendency of said sections to spread apart.

The two end portions are connected by an intermediate section which comprises a drip collar 5 and shanks 6 and 7 that connect the drip collar with the respective end portions 2 and 3. The drip collar or enlargement 5 preferably is about square in outline and has bevelled sides which meet to form a thin edge at the perimeter of the collar. The shanks 6 and 7, as illustrated, are tapered from the collar toward the ends 2 and 3 and they are also tapered vertically. That is, each shank has a thin or compara-

tively sharp upper edge 8 and it gradually increases in cross sectional width below this edge. This is clearly shown by the cross sectional Figures 4 and 5. I prefer also to make the upper and lower faces of the tie plate exactly alike so that it will make no difference which face is uppermost.

The sharp edges on the shanks 6 and 7 and collar 5 split and body of mortar that falls on the tie from above after the tie has once been secured in its operative position, and thus prevent the building up of a body of mortar on the tie with the consequent disadvantages above described. When this tie is in its proper position in a wall, the enlargement or drip collar 5 effectually prevents water from travelling across the tie from one wall to the other. Any water that runs down the inner face of the outer wall and strikes the tie can run across the tie until it reaches the part 5. It cannot travel any further, however, toward the inner wall but will simply run to the lowest point of the collar and drop off. In order to resist rusting of the tie, or any corrosion or galvanic action which might destroy it, I prefer to make the tie of cast iron since I have found that this material, when used in a location of this character will last as long as a brick wall. The outer surface rusts but the rusting does not progress at it does in other metals.

By using a tie of this construction in the walls, any possibility of water working across the air space from one wall to the other is absolutely prevented. Consequently, plaster can be applied directly to the inside surface of the inner wall and the necessity of using furring strips is avoided. There is also an advantage in having the drip occur at a fixed point between the

walls since it permits more accurate control of the drip and the collection and disposal of it at the bottom of the wall.

It will be appreciated that the present invention provides a wall tie which is as permanent as the wall itself, can be economically manufactured, is very convenient to use, and in fact has all the advantages of the brick tie with none of its disadvantages. I have described the wall tie above as used in a brick wall, but it will be appreciated that this tie can be used to advantage in any hollow wall of masonry construction.

Having thus described my invention, what I desire to claim as new is:

1. A cast iron wall tie having flat opposite end portions constructed to be anchored, respectively, in the inner and outer sections of a wall, the upper and lower surfaces of said end portions being corrugated, said end portions being tapered in width toward each other, and an intermediate section integral with said end portions and comprising a centrally disposed drip collar and shanks connecting said collar with said end portions, said shanks being tapered both vertically and longitudinally.

2. A cast iron wall tie having opposite end portions constructed to be anchored, respectively, in the inner and outer sections of a brick wall, and an intermediate portion integral with said end portions and comprising a centrally disposed drip collar and shanks connecting said collar with said end portions, each of said shanks having a thin upper edge extending longitudinally thereof and being tapered in vertical cross section, whereby they will split falling masses of mortar and prevent the accumulation of such masses on them.

JOHN J. MACK.
